UNITED STATES PATENT OFFICE.

ADNAK McMIURTRIE, OF NEW YORK, N. Y., AND LEWIS H. CHURCH, OF STAMFORD, CONNECTICUT, ASSIGNEES TO THOMAS & BETTS COMPANY, OF NEW YORK, N. Y., A CORPORATION OF NEW YORK.

ELECTRICAL-CONDUIT ATTACHMENT.

1,328,106.

Specification of Letters Patent.

Patented Feb. 9, 1915.

Application filed April 15, 1911. Serial No. 621,346.

To all whom it may concern:

Be it known that we, ADNAK McMIURTRIE, of New York, N. Y., and LEWIS H. CHURCH, of Stamford, Connecticut, have invented 5 certain improvements in Electrical-Conduit Attachments, of which the following description, in connection with the accompanying drawings, is a specification, like numerals on the drawings designating like parts.

10 This invention relates to electrical conduit systems and is of particular utility when embodied in electrical conduit members of the nature of outlet boxes, although we contemplate the use of our improvements 15 in any field for which they are adapted by their nature.

An important object of our invention is to provide means to effect a firm mechanical and electrical connection with such a box of 20 the tubular metallic armor sheath used to protect electrical conductors, whether such a sheath takes the form of a distinct entity, in which event it is usually known as "duct", or is formed as a unitary structure 25 with the electrical conductors, in which latter event it is usually known as "cable", and we will so designate it, hereinafter, using the term "cable" however broadly and not with any limited technical significance.

Among other important objects contributory to the above primary object, may be mentioned the requirement that the gripping member which we provide to be engaged 30 with the sheath shall form an extended binding contact with the article to be attached, as for example the "cable" above mentioned; also that it shall draw the "cable" toward the box, and shall prevent 35 movement of the "cable" away from said box either along the line of its axis, or by way of rotation.

The above objects may be provided for by any suitable construction, but we prefer to 40 make use of a retaining device taking the form of a draft screw, and which may be similar in general construction to the ordinary "stove bolt" of commerce, this being a well known mechanical element with 45 which workmen are familiar, so that they do not require special instruction to enable them to use it properly and it may be fitted by using labor of a less expensive character.

for that reason. We may provide such a "stove bolt" with a nut of special form to 50 serve as the gripping member, and for that purpose we prefer to provide a polygonal nut of trapezoidal contour, and to use in connection with such a nut a bolt which is arranged upon the wall of the box in such 55 fashion as to transfix the wall of the box, with the head of the bolt therein, the nut being located in a recessed portion of the lower wall of the box in communication with the 60 socket or seat usually provided in such 65 boxes to receive the sheath, an opening through the bottom of the box being provided also to pass the conductor into the box.

In accordance with our invention, the bolt 70 is placed in a substantially diagonal relation to the longitudinal axis of the sheath, and the walls of the recess are so arranged that when the head of the bolt is rotated the nut will be drawn along against the inner 75 wall of the recess, the latter serving as an abutment or forcing wall to hold the nut up to its work as it is drawn by the bolt into biting contact with the periphery of the sheath, and the bolt being tilted at such an angle to 80 the horizontal that the nut will be drawn upward at the same time, exerting an upward draft upon the periphery of the sheath with which the nut engages in a line contact, preventing both rotative and axial 85 placement of the sheath.

Another important object of our invention is to provide means for holding the nut or gripping member out of the path of the sheath at the time that the latter is being 90 connected to the box, thus obviating a source of frequent delay and inconvenience to the workman who fit such connections, for in boxes as used at present the retaining members are constantly falling into the path of 95 the sheath, requiring a care and attention which is a source of expense. For that purpose any suitable means may be provided, and as one convenient device we make use of a coil-spring upon the bolt, intervening between the nut and the bottom wall of the 100 box, so that the spring, being under compression, tends constantly to force the nut away from the socket or seat aperture for the sheath.

The various features of our invention will

be illustrated and described fully in the accompanying drawings and specification, and set forth in the claims.

In the drawings, Figure 1 is a view in plan looking from bottom to top of a box for electrical conduit, in the construction of which our invention has been embodied; Fig. 2 is a similar view in plan looking from top to bottom of said box; Fig. 3 is a vertical sectional view of said box on the line 3—3, Fig. 1 looking in direction of arrows; Fig. 4 is a view in perspective partly in section of the box shown in Fig. 1; Figs. 5 and 10 are views of gripping members of various forms; Figs. 6, 7, 8 and 9 are views similar to Figs. 1, 2, 3 and 4 respectively, of an electrical conduit box of modified form; and Fig. 11 shows a modified form of gripping member.

In the embodiment of our invention for illustration and description to enable ready and complete understanding of our improvements, the part designated by the reference numeral 1 is an "outlet box" or "cable box" of a type well known to those skilled in the art of installing electrical conduit systems, and may be of any suitable shape, material and general arrangement, the form herein shown by way of example being circular, of cast metal, and having several sockets, bushings or seats 2, with apertures 3, and rounded mouths or shoulders 4 of a type usually provided to receive sheaths, such as that shown at 5 for electrical conductors 6 provided with insulation 7, the type of conductor shown being what is known as "cable", its armor consisting of a spirally wound metal strip, the end 8 of which preferably abuts snugly against the shoulder 4 of the bushing.

In accordance with our invention, retaining or gripping members 9 are provided for the respective sheaths and may be of any form suitable to carry our invention into effect, each retaining member being shown in the instance illustrated as a bolt comprising a polygonal nut, best seen in Fig. 5, having a suitable operating member, such as the draft screw 10, which passes at 12 through an aperture 13 in the portion 14 of the bottom wall of the box, the bolt having a slotted head 16 to permit its operation by a screw driver in the hands of the operator, who may work from the face of the box opposite that containing the entrance to the bushings or sockets, usually the inner side of the cable box.

In accordance with an important feature of our invention the gripping device is constructed and arranged to be engaged with suitable abutment surfaces 18 and 19 provided upon the lower face of the bottom wall of the box, such surfaces constituting forcing walls, and for that purpose being so arranged that as the bolt is rotated the

nut will be drawn into contact with the sheath, and the sheath will be wedged between the seat for the sheath and the nut and at the same time the nut is drawn upward from the plane of the base, drawing 70 with it the sheath, so that the latter will be seated firmly in its socket against the shoulder 4.

In accordance with another important feature of our invention we prefer to tilt the 75 abutment surfaces, as illustrated, so that the gripping side 20 of the nut will be engaged with the periphery of the sheath in a longer region of physical and electrical contact than would be the case were a rectangular 80 nut drawn along abutment surfaces perpendicular to the base of the box. This line contact of the gripping member with the periphery of the sheath serves to hold the sheath firmly against rotative and axial displacement and we may provide for it by any suitable construction. For example, as illustrated in Figs. 6-11 inclusive, a gripping nut 30 of trapezoidal contour may be utilized and the long gripping side 32 of this 90 nut will be engaged with the periphery of the sheath 50 in a longer region of physical and electrical contact than would be the case were the nut of merely rectangular contour, so that a good physical and electrical 95 connection is insured. With such a nut, the abutment surface 88 may be perpendicular to the base of the box, which will otherwise preferably be substantially like the box already described.

As hereinbefore indicated, we prefer to provide also means acting normally to hold the nut out of the path of the sheath, and as one suitable form of device for this purpose, we have shown at 40 a coiled spring upon the shank of each bolt, under compression between the nut and the draft wall portion 14 of the bottom wall of the box, through an aperture 13 in which extends the shank of the bolt, and we prefer to have the recess in which each nut lies of a sufficient size to receive the nut snugly, when thus positioned by the spring, so as to clear the socket 3 entirely, and thus the workman is not hampered in his insertion of each sheath and 105 conductor.

The numeral 60 designates the usual central hole or bushing provided to receive a gas pipe or other means of support for these boxes, which are commonly used upon ceilings and in similar situations, a set screw 61 being provided ordinarily to hold the box in adjusted position. The usual screw holes 62 in the base may also be provided.

If desired, and it will usually be found 125 preferable, the gripping nuts may each be serrated along the gripping side 66, as shown in Figs. 5 and 11, those serrations aiding to prevent the rotative displacement of the sheath when connected.

Having illustrated and described our invention thus fully, and suitable means for carrying the same into effect, we wish it understood that we do not limit ourselves to the specific construction and materials shown and described by way of example, nor in general do we limit ourselves otherwise than as set forth in the claims read in connection with this specification.

10. What we claim as new and desire to secure by Letters Patent is:—

1. A gripping device for an armor sheath, said device comprising a gripping member and actuating means therefor, said gripping member and actuating means being movable relatively to each other; and means to support said gripping member movably in a path tangent to the periphery of said armor sheath and into diagonal contact with 20 one side of said periphery.

2. In a conduit fitting, a wall member having an orifice for the passage of an armor sheath and a recess for a gripping device for said sheath; and a gripping device comprising a gripping member in said recess and separate actuating means for said gripping member; said recess being located along one side of, and longitudinally diagonal to, said orifice, and having a forcing 30 wall inclined toward said orifice at an angle to a plane passed through the longitudinal axis of said orifice, and said wall serving to direct said gripping member into diagonal line contact with said sheath.

3. An electrical conduit member; comprising a seat portion to receive a conductor sheath; and a portion opposed to said seat, and including a plurality of forcing surfaces to receive and direct a gripping member; 40 and a gripping member movable bodily along said surfaces; one of said forcing surfaces being tilted at an angle to a plane passed through the longitudinal axis of said seat, and another of said surfaces lying at 45 an angle to a plane perpendicular to said axis, said surfaces cooperating to maintain said gripping member in position for movement into diagonal line contact with said sheath, substantially as, and for the purpose, 50 set forth.

4. An electrical conduit member; comprising a seat portion to receive a conductor sheath; and a portion opposed to said seat, and including a plurality of abutment surfaces to receive a gripping member movably; said surfaces being tilted away from said seat to present said gripping member in position for line contact with said sheath, a polygonal gripping member movable along 60 said surfaces, in a direction diagonally tangent to, and into retentive contact with, said sheath; and an operating member to actuate said gripping member, substantially in the manner and for the purpose set forth.

65. 5. An electrical conduit member of the

nature of an outlet box; comprising a wall provided with a socket for a conductor sheath; and a gripping device comprising a grip and separate actuating means therefor, said wall having a forcing surface arranged at an angle to a plane passed through the longitudinal axis of said socket to direct said grip into diagonal line contact with the periphery of said sheath. 70

6. An electrical conduit member of the 75 nature of an outlet box; comprising a box wall provided with a socket to receive a conductor sheath; said box wall having a recessed portion in communication with said socket, said recess being located along one side of, and longitudinally diagonal to, said socket, and a gripping device comprising a grip and separate actuating means for same, said grip being supported movably in said recessed portion and directed by said wall 80 into retentive contact with said sheath.

7. An electrical conduit member of the 90 nature of an outlet box; comprising a box wall provided with a socket to receive a conductor sheath, said box wall having a recessed portion in communication with said socket, said recess being located along one side of, and longitudinally diagonal to, said socket; and a gripping device comprising a grip, and separate actuating means therefor, said grip being supported movably in 95 said recessed portion, and said actuating means being operable from the other face of said box wall relatively to said socket, to move said gripping device into diagonal line retentive contact with said sheath.

8. An electrical conduit member of the 100 nature of an outlet box; comprising a box wall provided with a socket to receive a conductor sheath; said box wall having a recessed portion in communication with said socket, said recess being located along one side of, and longitudinally diagonal to, said socket; a grip supported movably in said recess, and a screw, extending through said 105 box wall with its head upon the face of said box wall opposite that containing said socket, and its shank in actuating connection with said grip. 110

9. An electrical conduit member of the 115 nature of an outlet box, having a bottom wall provided with a plurality of sockets for conductor sheaths, and having recessed portions in communication with certain of said sockets, each to receive a gripping member, the walls of said recessed portions comprising respectively a pair of forcing surfaces inclined respectively one at an angle to a plane passed through the longitudinal axis of said sheath, and the other at an angle 120 to a plane perpendicular to said axis, said member having also draft-walls near said forcing surfaces, and retaining-bolts, comprising each a draft screw and a cooperating 125 polygonal gripping nut two of whose 130

sides are engaged with a pair of said forcing surfaces, and, a third side is presented for retentive engagement in diagonal line contact with a sheath in its socket, said 5 draft screws extending one from each of said nuts through said respective draft portions of said bottom wall, said draft screws having operating heads operable from within said box on the other side of said bottom 10 wall.

10. The combination with an electrical conduit member of the nature of an outlet box, having sheath-seats and bolts with gripping nuts for retentive engagement with 15 said sheaths, of springs acting to hold said nuts out of the path of said sheaths, respectively; substantially as described.

11. The combination with an electrical conduit member of the nature of an outlet 20 box, having sheath-seats and bolts with gripping nuts for retentive engagement with said sheaths, of coil springs surrounding said bolts and acting to hold said nuts away from said seats; substantially as described.

25 12. The combination with an electrical conduit member of the nature of an outlet box, having a sheath-seat beneath its wall; of a retaining-bolt passing through said

wall; a gripping nut on said bolt for retentive engagement with said sheath; and a 30 spring between said nut and wall to hold said nut normally out of the path of said sheath.

13. The combination with an electrical conduit member having a seat for a conductor sheath, of a gripping device comprising an operating member located alongside of 35 said seat and longitudinally diagonal with reference thereto, and a gripping nut of trapezoidal contour operable along said operating member into engagement with said sheath, said conduit member having a forcing wall presented toward said sheath in a position parallel to the axis thereof; and said trapezoidal nut presenting surfaces for 40 line engagement with said forcing surface and the periphery of said sheath respectively.

Signed at New York in the county and State of New York this 13th day of October 50 1914.

ADNAH McMURTRIE.
